(57) **CLAIM**

The ornamental design for a toy police car, as shown and described.

DESCRIPTION

FIG. 1 is a front-top perspective view showing a toy police car;

FIG. 2 is a rear-top perspective view of FIG. 1;

FIG. 3 is a bottom-front perspective view of FIG. 1;

FIG. 4 is a bottom-rear perspective view of FIG. 1;

FIG. 5 is a top plan view of FIG. 1;

FIG. 6 is a bottom plan view of FIG. 1;

FIG. 7 is a front elevation view of FIG. 1;

FIG. 8 is a rear elevation view of FIG. 1;

FIG. 9 is a left side view of FIG. 1; and,

FIG. 10 is a right side view of FIG. 1.

1 Claim, 10 Drawing Sheets
